UNITED STATES PATENT OFFICE.

NELSON M. LANGDON, OF CHESTER, NEW JERSEY.

APPARATUS FOR GENERATING GAS.

SPECIFICATION forming part of Letters Patent No. 276,432, dated April 24, 1883.

Application filed October 5, 1882. (No model.)

To all whom it may concern:

Be it known that I, NELSON MILTON LANGDON, of Chester, in the county of Morris and State of New Jersey, have invented certain new and useful Improvements in Apparatus for Generating Gas; and I do hereby declare the following to be a full, clear, and exact description of the invention, such as will enable others skilled in the art to which it pertains to make and use the same.

My invention relates to an improvement in gas generators, and more particularly to that class thereof in which gas is produced by the dissociation of steam in the presence of incandescent carbonaceous fuel, the object of the invention being to superheat commingled steam and air, previous to their introduction into the fuel-chamber, by the heat of conduction and radiation derived from the fuel itself, the superheated steam and heated air imparting their sensible heat to the fuel in their passage through it, thus assisting in maintaining it normally in a state of incandescence, or at a temperature sufficiently high to effect the dissociation of the steam and reducing the amount of air required to the minimum, whereby a superior quality of gas is obtained and the expense of its production decreased.

With this object in view my invention consists in certain details of construction and combinations of parts, as will be more fully described, and pointed out in the claims.

In the accompanying drawings, Figure 1 is a view in vertical section of a gas-generator constructed in accordance with my invention, and Fig. 2 is a view thereof in transverse section, taken through the superheater.

A is an upright cylindrical furnace, provided at its upper end with a hopper, B, and a bell, C, the latter being depended by a link, D, from a weighted lever, E, which maintains the bell in its closed adjustment. Flaring orifices F, leading from the top of the furnace into the upper generating-chamber, G, are designed to permit the introduction of rods thereto for manipulating the fuel, when necessary. The gas generated is conveyed away, for use or storage, by means of a flue, H, leading out of the said chamber G. A cylindrical structure, I, rising centrally within the furnace and culminating in a conical top, J, incloses the annular superheating-chamber K. The lower

portion of the furnace is divided into three compartments or generating-chambers, L, by radial piers M, which extend upward to the base of the conical top J of the structure I, the said top operating, in virtue of its conical form, to deflect the fuel equally into the said chambers. Each section of the furnace inclosed by the said piers is provided with a tier of flaring orifices, M', to permit the introduction of rods into the chambers L for the purposes of manipulating the fuel and breaking down any clinkers which may be formed. Each of the said furnace-sections is also provided with a door, N, for the withdrawal of the fuel-ash. Communication between the several chambers L and the annular superheating-chamber K is established through openings O, formed under the lower edge of the structure I. A cylindrical pipe, P, supported on the floor of the furnace and rising centrally within the superheater, is designed to convey the commingled air and steam to its upper extremity, where it impinges on the base of the conical top J, being deflected by the same into the annular superheating-chamber K, formed between the structure I and the said pipe P. A pipe, R, provided at its outer end with a steam-jet blower, S, and with orifices T for the admission of air, is designed to convey the said steam and air to the pipe P. The pipe R is also provided with a throat, U, in which the steam and air are commingled, the relative quantities of each admitted into the pipe being regulated by the valves V and W, respectively.

Having described in detail the construction of my improved generator, I will now proceed to set forth the mode of its operation.

After filling the furnace with any suitable carbonaceous fuel, the same is ignited and allowed to burn until it becomes incandescent, or nearly so. Steam and air are then admitted into and commingled in the pipe R. Thence passing to the pipe P, in which they will rise, being deflected over its upper edge into the annular superheating-chamber K, from which they will enter the chambers L of the furnace through the orifices O. In the transit of the steam and air through the annular superheating-chamber K they will become very highly heated by the heat of conduction and radiation derived from the combustion of fuel.

in the furnace. After escaping into the chambers L, as above described, they will rise through the fuel and impart their sensible heat to it, the steam being at the same time decomposed into its constituent elements, hydrogen and oxygen, the latter combining with the carbon of the fuel to form carbonic oxide. These gases ascend to the top of the furnace, being finally conveyed away, for use or storage, 5 by the flue H. The ash of the fuel forms more or less clinkers, which bridge the space between the piers and support the fuel above the floor of the furnace, permitting the accumulations of ash and clinkers thereon to be withdrawn without disturbing the body of the burning fuel. The object of admitting air into the furnace is to support the combustion of the fuel therein, and thus counteract the effect 10 of the steam-blast, the tendency of which is to lower the temperature of the fuel below the degree of heat at which its dissociation is effected; but inasmuch as the nitrogen of the air impairs the combustible qualities of the gases generated it is desirable to reduce the 15 quantity required to the minimum amount. This result is effected in the generator herein shown by superheating the steam and air, previous to their introduction into the fuel-chamber by the heat of conduction and radiation derived from the fuel itself, the sensible heat 20 imparted to the fuel by the steam and air assisting very materially in maintaining it in a state of incandescence.

While my generator may be employed to 25 generate illuminating or heating gases, it will be found to be admirably adapted to the production of gases of high thermic power, such as are used in metallurgic processes.

It is apparent that the generator shown 30 herein may be greatly modified in construction without departing from my invention. I would therefore have it understood that I do not limit myself to the exact construction shown and described; but that I hold myself 35 at liberty to make such slight changes and alterations as fairly fall within the spirit and scope of my invention.

Having fully described my invention, what I claim as new, and desire to secure by Letters 40 Patent, is—

1. The combination, with a furnace, of a superheater consisting of a hollow structure

closed at the top, and having a series of apertures extending around its base, said structure resting on the bottom of and rising centrally 55 within the furnace, and means to effect the transit of commingled steam and air from the base to the top of the superheater and back again, and to deflect it into the furnace through the apertures in the base of the superheater, substantially as set forth.

2. The combination, with a furnace, of a superheater consisting of a hollow structure closed at the top, and having a series of apertures extending around its base, said structure resting on the bottom of and rising centrally 60 within the furnace, a pipe rising within and nearly to the top of the superheater, and means to introduce commingled steam and air into the base of said pipe, substantially as 65 set forth.

3. The combination, with a furnace, of a superheater consisting of a hollow structure closed at the top, and having a series of apertures extending around its base, said structure resting upon the bottom of and rising centrally 70 within the furnace, a pipe rising within and nearly to the top of the superheater, and a pipe to introduce commingled steam and air 75 into the base of the pipe located in the superheater, substantially as set forth.

4. The combination, with a furnace, of a superheater consisting of a hollow structure closed at the top, and having a series of apertures extending around its base, said structure resting on the bottom of and rising with 80 in the furnace, means to deflect commingled steam and air through the superheater and into the furnace in the manner described, and piers radiating from the superheater and dividing the lower portion of the furnace into 85 isolated compartments, steam and air being introduced into each compartment from the superheater, and the outer wall of each compartment having a door and a tier of flaring 90 orifices, substantially as set forth.

In testimony whereof I have signed this specification in the presence of two subscribing witnesses.

NELSON MILTON LANGDON.
